UNITED STATES PATENT OFFICE.

FRANZ PUENING, OF PITTSBURGH, PENNSYLVANIA.

CRACKING OILS.

Application filed May 26, 1919. Serial No. 299,973.

In the cracking of heavy oils or tars into oils of lower boiling points solid carbon is formed mainly on the heated shell of the still containing the oil. This carbon because of the high pressure and temperature under which the cracking is carried out, is a great danger to the heated shell. In order to alleviate this danger different means have already been proposed as for instance to drive the oil with high speed over the heated surfaces or to use only vertical heated surfaces or to provide spaces in which the carbon can collect without danger or to clean the heated surfaces during operation. But the particular methods proposed heretofore have not given full satisfaction and it is the object of my invention to supply a new method and apparatus for treating the oil, which while making use of the enumerated means for alleviating the carbon trouble, employs them in a new and original way, so that the carbon danger is overcome entirely.

In the accompanying drawings and in the following specification I have described a preferred process and apparatus for carrying out my invention. It is to be understood however, that the specific disclosure is for the purpose of exemplification only, and that the scope of the invention is defined in the following claims.

Referring now to the following drawings, Fig. 1 illustrates in vertical section an apparatus for carrying out my invention,

Fig. 2 is a plan view of the same apparatus,

Fig. 3 is a vertical section through a larger apparatus of the same type,

Fig. 4 is a plan view of that apparatus,

Fig. 5 shows on an enlarged scale certain elements of the apparatus.

Referring now to the first embodiment of my invention shown in Fig. 1 it will be seen to comprise a vertical retort 6, containing the oil to be cracked, the level of which is shown at 7. The furnace 8 supplies the cracking heat. The combustion gases pass upwards in the vertical flue 9 and through openings 10 into chamber 11 surrounding the retort. The gases then pass around the retort and disappear through openings 12 into flue 13 which is connected to the stack. The openings 10 and 12 are adjusted so that the heat conveyed to the heated surfaces of the retort is substantially the same everywhere. Only a middle portion of the vertical walls is thus heated; an upper portion

and a smaller lower portion are unheated. The bottom 14 of the retort is unheated.

In the retort is a vertical duct 15, open on its upper and lower end, whereby the space 60 in the retort is separated into an annular space 16 outside and an essentially cylindrical space 17 inside the duct. The two spaces communicate with each other above and below the duct.

Steel wire brushes 18 or scrapers or equivalent means are attached to the duct in such a position, that their ends press against the inside surfaces of the retorts, which are subjected to the heat from the furnace. One 70 of the scrapers is shown on an enlarged scale in Fig. 5, in which 19 represents part of the heated retort wall and 20 part of the duct. The scraper 18 penetrates the wall of the duct through an opening of suitable size. 75 The scraper is linked to the duct by means of the elastic steel band 21 and bolts 22 and 23. The pressure of the scraper against the retort wall is regulated by turning nut 24 of bolt 23. The scrapers are dragged 80 over the retort wall by rotating the entire duct. To this purpose a shaft 25 is set up in the center of the retort and held in position by bearings 26 and 27. This shaft is connected to the duct by spokes 28. On its 85 uppermost end it is geared to another shaft 29 by a pair of bevel gears 30. The driving of the shaft may be done by any suitable machinery. To avoid a high sidethrust on the bearings the scrapers are distributed over 90 the circumference of the duct in two rows and their location and number is such that every part of the heated retort surface is under their reach.

Under the action of the heat from the furnace the oil in the annular space 16 becomes hot and specifically lighter and the gasoline vapors and permanent gases produced in this space tend upwards and act as a powerful agent, similar to the air in an air lift well 95 pump. In consequence a rapid upward movement of the oil in the annular space sets in. When the oil has reached the level at 7 it gives off the gasoline vapors and gases and passes towards the center of that level 100 and subsequently is drawn through the inside of duct 15 down to its lower end, from where it is drawn again to the annular space 16 and forced to repeat its circle.

The diameter of the duct 15 is made as 110 large as practically possible, whereby the speed of the liquid in the annular space is

made high and the downward speed in the duct slow, with the result that the settling out of carbon on the heated surfaces in the annular space is made difficult, while its precipitation on the inside surfaces of the duct and on the unheated bottom of the retort is made easy. Also the carbon, which is scraped off the heating surface, is by means of the high speed of the oil in the annular space carried over into the inside of the duct, where it settles out. This settling out of the carbon is facilitated by a number of surfaces in the duct such as the spokes 28 or the steps 31, shown only in Fig. 1, which are built into the duct for the convenience of the men, who have to inspect the retort. The number of such surfaces can of course be increased in any desired degree by adding other surfaces for the mere purpose of catching or filtering out the carbon. Thus a screen 31^a is provided at the lower end of duct.

In order to allow inspection of the heating surface, the walls of the duct are composed of panels, which swing on hinges. The arrangement is shown in Fig. 5 in which 32 is a hinge for the panel 33; 28 are again the spokes connecting the duct to the shaft. A bolt 34 is keeping the panel closed while the still is in operation.

A still, larger than the one now described, is shown in Figs. 3 and 4. It consists of two retorts 35 and 36. All the features described in connection with the one retort are present in each of these two retorts. But an additional provision has been made to secure complete circulation of the oil through both of the retorts. For this purpose the upper ends of the ducts 37 and 38 are closed by covers 39 and 40 with openings 41 and 42. The opening 41 is connected through the bent pipe 43 to the space above cover 40, and the opening 42 through bent pipe 44 to the space above cover 39. The two bent pipes are fastened to the shells of the retorts and do not take part in the rotation of the ducts and covers. Their lower ends facing the two covers are formed into large flanges 43^a and 44^a and are gently pressed against the covers, whereby sufficient tightness of connection at this point is assured.

Under the action of the furnace heat, the oil in the annular space 45 in retort 35 moves upwards into the space above the cover, 39, but is prevented from entering duct 37 by means of cover 39 and flange 43^a and forcibly conducted through pipe 44 into duct 38. In the same way the oil moving upwards in the annular space 46 in retort 36 is forcibly conducted through pipe 43 into duct 37. It is evident that in this way any number of retorts may be connected and perfect circulation established through all of them.

The new method and apparatus is equally well adapted for dealing with oils and tars, mentioned in the beginning, because similar

difficulties are experienced in the treatment of both, especially if they already contain much free carbon. The cracking may thereby be unintentional. For instance, when subjecting tars to heat, even if distillation only is aimed at, an unintended cracking of a portion of the molecules goes on, with simultaneous formation of carbon and permanent gases. The condition in the stills is therefore much the same as where cracking is intentionally carried out. The term "cracking oil" in the following claims therefore covers the cracking of hydrocarbons where it is done intentionally, as in the case of petroleum, and where it is unintentional, accompanying some other process. In either case does the new method and apparatus provide the means to overcome the dangers and disadvantages resulting from the cracking.

I claim:

1. The method of cracking oil, which consists in subjecting an annular column of oil to a cracking heat, while effecting a rapid movement of the oil by thermo-siphonic action, and concurrently mechanically removing the carbon from the heated portions of the walls surrounding the column of oil.

2. The method of cracking oils, which consists in maintaining a substantially vertical annular column of the oil, supplying a cracking heat to only the sides of the column thereby causing a rapid upward movement of the column, separating gas bubbles in a space at the upper end and inside of the annular column, leading the quieted dense liquid through the space inside of the annular column back to the bottom of the column and mechanically cleaning the heated walls of the column.

3. A method of cracking oil, which consists in circulating the oil by thermo-siphonic action in a continuous cycle through a space having a heated surface and through an unheated space, and mechanically separating the carbon formed on the heated surface and collecting it in the unheated space.

4. A method of cracking oil, which consists in effecting a relatively rapid circulation of the oil by thermo-siphonic action through a space provided with a heated vertical wall and subsequently causing the oil to flow at a relatively lower speed through a space of reduced temperature, and mechanically separating the carbon from the heated wall and collecting it in the space of relatively reduced temperature.

5. The method of cracking oil, which consists in maintaining a substantially vertical annular column of the oil surrounding a central space, supplying a cracking heat to only the outer sides of the column, thereby causing a rapid upward movement of the column mechanically separating the carbon from the heated walls of the column, and carrying it

into the space inside of the annular column separating it therein from the oil.

6. A process of cracking oil, which consists in enclosing the liquid material in a vertical retort containing an inner shell having a passage through its interior and mechanical cleaners for the retort walls, applying a cracking heat to the vertical walls only of the retort, thereby causing a rapid movement of the oil over the heated surfaces, causing the shell and the cleaners to rotate, removing the carbon from the heated surfaces and carrying it with the oil into the inside of the shell and precipitating it there-
15 in and upon the bottom of the retort.

7. A process of cracking oil, which consists in enclosing the oil in a series of vertical retorts containing inner shells and mechanical cleaners operating on the walls of the retorts, applying a cracking heat to the walls of the retorts, causing a rapid movement of the oil through all of the retorts and inner shells by means of thermo-siphonic action, rotating the shells for the passage of the oil and cleaners thereby accelerating the speed of travel of the oil in contact with the retort walls and, by the concurrent action of the mechanical cleaners and the rapidly moving oil, removing the carbon from the heated walls and collecting it at places remote from cracking heat.

8. The method of cracking oil in a plurality of substantially vertical stills having interior return shells for the passage of the oil and mechanical cleaners operating on the still walls, which consists in subjecting the stills to heat and thereby developing upward currents of the heated oil by thermo-siphonic action, separating the gas bubbles in spaces at the upper end of each still, leading the liquid from said spaces into the passage within the return shell of the next still and thereby effecting a cyclic movement through all the stills, and concurrently mechanically cleaning the heated wall surfaces of the stills.

9. An oil cracking apparatus comprising: a heating chamber adapted to produce a heated zone; a substantially vertical boiler disposed therein and having its extremities extended beyond the heated zone, a substantially vertical shell for the passage of the oil located within the boiler and having a passageway therethrough opening at its ends into said boiler, the space between the boiler and shell being of substantially uniform cross-sectional area in different horizontal planes whereby the speed of the oil is substantially uniform at all points in said space, mechanical scraper elements carried by the outer wall of said shell and adapted to operate on the inner wall surface of the boiler, and means for effecting concurrent rotation of said shell and mechanical scrapers,

10. An oil cracking apparatus comprising: a heating chamber adapted to produce a heated zone; a substantially vertical boiler disposed therein and having its extremities extended beyond the heated zone, a substantially vertical shell for the passage of the oil located within the boiler and having a passageway therethrough opening at its ends into said boiler, the space between the boiler and shell being of substantially uniform cross-sectional area in different horizontal planes whereby the speed of the oil is substantially uniform at all points in said space, mechanical scraper elements adapted to operate on the inner wall surface of the boiler, and means for effecting concurrent rotation of said shell and mechanical scrapers.

11. An oil cracking apparatus comprising: a substantially cylindrical shell, an interior shell within said shell open at top and bottom to the interior of the outer shell and forming therewith a passageway of restricted cross-sectional area from bottom to top, said passageway being of substantially uniform cross-sectional area in different horizontal planes whereby the speed of the oil therethrough is substantially uniform at all points therein, and rotatable mechanical scrapers engaging the inner wall surface of the outer shell.

12. An oil cracking apparatus comprising, in combination: a plurality of substantially vertical shells, an interior open shell providing a through passage within each shell, mechanical cleaning means operating on the inner wall surface of each outer shell, and a flow connection between the duct of each shell and the surrounding chamber of another shell.

13. In an oil cracking apparatus, in combination: a substantially vertical still, a return shell within said still terminating below the top thereof to provide a quieting space in the upper region of the still, the return shell being open at top and bottom to the interior of the still said still and shell forming between them a passageway of restricted cross-sectional area from bottom to top, said passageway being of substantially uniform cross-sectional area in different horizontal planes whereby the speed of the oil therethrough is substantially uniform at all points therein, and mechanical cleaning means engaging the wall of the still.

14. In an oil cracking apparatus, in combination: a plurality of substantially vertical stills, a return shell providing a through passage within each still terminating below the top thereof to provide a quieting space located in the upper region of the still, a flow pipe connection between the upper end of each return shell and the quieting space of another still above its shell, and mechanical cleaning means engaging the inner wall surface of each still.

- 4
15. In an oil cracking apparatus, in combination: a plurality of substantially vertical stills, a rotary shell for the return passage of the liquid within each still terminating below the top thereof to provide a quieting space located at the upper region of each still, a stationary flow connection between the upper end of each return shell and the quieting space of another still, and mechanical cleaning devices carried by the respective return shells and engaging the inner wall surfaces of their corresponding stills.
16. The method of cracking oil in a plurality of substantially vertical stills having

interior return shells and mechanical cleaners operating on the still walls, which consists in subjecting the stills to heat and thereby developing upward currents of the heated oil by thermo-siphonic action, separating the gas bubbles in spaces at the upper end of the stills, leading the liquid from said spaces into the return shell of the next still and thereby effecting a movement of the liquid throughout all the stills, and concurrently mechanically cleaning the heated wall surfaces of the stills.

FRANZ PUENING.
